FEED AND DISCHARGE CONTROL MEANS
FOR PAIRED ROLLS WITHIN ROTARY
HOUSINGCharles A. Dreisbach, Yonkers, N. Y., assignor
to Standard Radial Blast Corporation, Yonkers,
N. Y., a corporation of New York

Application February 5, 1946, Serial No. 645,541

4 Claims. (Cl. 241—97)

1

The present invention relates to improvements in grinding-mills of the type adapted to crush ores, slag, cinders, and other friable materials, and relates more particularly to grinding-mills of the type referred to and is characterized by an eccentric crushing-roll coacting with a central crushing-roll in combination with related features as set forth in the appended claims. The present invention constitutes improvements upon the structure disclosed in U. S. Patent No. 1,776,654.

One of the main objects of the present invention is to provide a grinding-mill having superior construction and arrangement of parts, whereby weaknesses and other defects in prior types of grinding-mills are largely obviated.

Another and more specific object of the present invention is to provide a superior grinding-mill combining reliability of operation with low cost for manufacture.

A further object of the present invention is to provide a grinding-mill having superior resistance to wear by the action of abrasive material being ground.

Still another object of the present invention is to provide a grinding-mill of the type having a pair of coacting crushing-rolls and provided with a superior construction and arrangement of parts, whereby the structure has maximum resistance to the severe shocks incident to the functioning of the said crushing-rolls.

A still further object of the present invention is to provide a grinding-mill having a superior construction and arrangement of parts for effecting the discharge of its contents.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a top or plan view of a grinding-mill embodying the present invention;

Fig. 2 is a view of the left side of the grinding-mill;

Fig. 3 is a view of the right side of the grinding-mill;

Fig. 4 is a broken transverse sectional view taken on the line 4—4 of Fig. 2;

Fig. 5 is a perspective view of the feed-chute and discharge-chute, together with the control mechanism for coincidentally tilting the same; and

2

Fig. 6 is a transverse sectional view taken on the line 6—6 of Fig. 3.

The particular grinding-mill herein chosen for purposes of illustrating one form of the present invention, includes a drum-like revolving housing generally designated by the reference character 10 and including a cylindrically-contoured peripheral wall 11 and two ring-like side-walls 12 and 13 suitably braced and welded or otherwise rigidly secured at their outer edges to the said peripheral wall.

Rigidly secured to the outer face of the left side-wall 12 of the housing 10, is a concentric driving-gear 14 and a concentric track-ring 15 which latter is preferably smaller in diameter than the diameter of the said driving-gear, and rests upon two idler rolls 16 and 17 supported in suitable bearings 18 mounted upon a left frame-member 19.

20 The right side-wall 13 of the housing 10, has rigidly secured to its outer face a concentric driving-gear 20 and a concentric track-ring 21. The said track-ring 21 rests upon idler rolls 22 and 23 mounted for rotation in suitable bearings 24 supported on the right frame-member 25.

Extending centrally through the housing 10 and projecting beyond each of the respective opposite sides thereof, is a center-roll shaft 26 supported for rotation at its respective opposite ends in similar journals 27—27.

35 One of the journals 27 above referred to is mounted at the upper end of a frame-standard 28 projecting upwardly from the central portion of the left frame-member 19. Interposed between the upper surface of the frame-standard 28 and the journal 27 supported thereon, are a plurality of helical shock-absorbing springs 29 constructed and arranged to cushion downward shocks impinging upon the shaft 26.

40 The journal 27 adjacent the right end of the center-roll shaft 26 is supported on a frame-standard 30 projecting upwardly from the right frame-member 25. Interposed between the upper end of the frame-standard 30 and the adjacent journal 27 are also a plurality of helical shock-absorbing springs 29.

Rigidly secured to the right end of the center-roll shaft 26 is a sprocket-wheel 31, while just inwardly of the said sprocket-wheel a flywheel 32 is also rigidly connected to the said shaft 26, as is especially well shown in Fig. 4.

Extending over the sprocket-wheel 31 of the center-roll shaft 26 is a sprocket-chain 33 which 55 also extends over a sprocket-wheel 34 rigidly

mounted upon a drive-shaft 35 adjacent the outer end thereof.

The drive-shaft 35 above referred to extends cross-wise in front of the rotary housing 10 and is supported in a journal 36 (Fig. 3) which is supported on the right frame-member 25. At its inner end, the drive-shaft 35 has rigidly attached to it a pinion 37 which meshes into and drives a gear-wheel 38 rigidly mounted upon a countershaft 39, as is indicated in Fig. 3. The said countershaft 39 extends crosswise in front of the housing 10 and is journaled adjacent each of its respective opposite ends in bearings 40—40, one of which is supported on each of the frame-members 19 and 25, as is indicated in Fig. 1.

The countershaft 39 has rigidly secured to it two spaced-apart pin-type pinions 41—41 respectively meshing into the left and right driving-gears 14 and 20, to effect the rotation of the housing 10 and the parts carried thereby through power applied to the drive-shaft 35.

From the foregoing it will be apparent that the drive-shaft 35 will effect the rotation of both the center-roll shaft 26 and the housing 10 in the same direction but with the said center-roll shaft turning more rapidly than does the housing 10.

Rigidly mounted upon the center-roll shaft 26 in line with the interior of the housing 10, is a center grinding-roll 42 having a toothed periphery and flanked on each of its respective opposite sides by stationary side-plates 43 and 44. The left side-plate 43 is rigidly supported upon the left frame-member and has a circular outer periphery closely approaching in size the interior periphery of the rotary left side-wall 12 of the housing 10, as is indicated in Fig. 6.

In a similar manner, the stationary right side-plate 44 is rigidly supported by the right frame-member 25 and has a circular outer periphery but slightly smaller in diameter than the inner periphery of the ring-like right side-wall 13 of the housing 10.

Extending through the housing 10 in parallelism with the center-roll shaft 26 is an eccentric-roll shaft 45 having rigidly mounted on its center portion an externally-toothed eccentric grinding-roll 46 which coacts with the toothed periphery of the center grinding-roll 42 to effect the grinding of friable material, in a manner as will hereinafter appear.

The left end of the eccentric-roll shaft 45 projects outwardly through the left stationary side-plate 43 at the left of the structure, through an arcuate clearance-slot 47 in the said side-plate. Similarly, the right end of the shaft 45 projects outwardly through an arcuate clearance-slot 48 formed in the stationary right side-plate 44.

The left end of the eccentric-roll shaft 45 is journaled in the lower inner end of an L-shaped guide-arm 49 having its outer end rigidly secured to a coupling-shaft 50, as is especially well shown in Fig. 1.

The coupling-shaft 50 above referred to is located outside of the housing 10 and extends transversely across the front thereof for being journaled at its respective opposite ends in bearings 51—51, each carried at the upper end of two similar frame-standards 52—52. One of the said frame-standards 52 extends upwardly from the forward portion of the left frame-member 19, while the companion frame-standard extends upwardly from the right frame-member 25.

In a manner similar to the mounting of its left end, the right end of the eccentric-roll shaft 45 is journaled in the lower inner end of an L-shaped

guide-arm 53 of a character similar to the guide-arm 49 before described.

Like the guide-arm 49 the outer end of the guide-arm 53 is rigidly mounted upon the coupling-shaft 50 adjacent the right end thereof so that the coupling-shaft 50 may act as a rigid coupling to confine the two guide-arms 49 and 53 to simultaneous and equidistant swinging-motion.

For the purpose of enabling the rotary-housing 10 to continuously lift and supply material to be ground between the center grinding-roll 42 and the eccentric grinding-roll 46, the interior of the said rotary-housing is provided with an annular series of lifting-plates or lifting-ledges 54 welded or otherwise rigidly secured to both the peripheral wall 11 and the side-walls 12 and 13. The said lifting-plates, it may here be noted, also serve to elevate material to effect its discharge from the housing in a manner as will be herein-after described.

For the purpose of guiding friable material to a position between the grinding-rolls 42 and 46 as such material is elevated by the lifting-plates 54, a pivotal feed-chute 55 is employed. The said feed-chute is mounted at its lower inner end with capacity for turning movement upon and relative to a shaft 56 mounted for turning movement adjacent each of its respective opposite ends in the stationary side-plates 43 and 44 but projecting outwardly through each of the latter.

At its right end the shaft 56 of the feed-chute 55 has rigidly coupled thereto a V-shaped lever 57 having two diverging-arms 58 and 59, each of which is pierced at its outer end for the sliding reception respectively of the outer ends of two corresponding guide-rods 60 and 61. Each of the guide-rods 60 and 61 just referred to is pivoted at its inner end to the outer end of a lever-arm 62. The said lever-arm is located exteriorly of the right side-plate 44 and is mounted upon the right end of the shaft 56 just inwardly of the lever 57, but with capacity for slight turning movement with respect to the said shaft, as is also the feed-chute 55. The hub of the lever-arm 62 extends inwardly through the adjacent right side-plate 44 into coupled engagement with the adjacent end of the feed-chute 55 so as to be substantially rigid therewith.

Each of the guide-rods 60 and 61 above referred to is encircled by one of two helical compression-springs 63—63. One of the said springs is compressed between the under surface of the upper arm 58 of the lever 57 and the upper surface of the lever-arm 62 while the other of said springs is compressed between the upper surface of the lower arm 59 and the under surface of the lever-arm 62. The arrangement of the springs 63—63 is such that they serve to normally centralize the lever-arm 62 with respect to the arms 58 and 59 of the V-shaped lever 57 and afford a yielding coupling therebetween.

Rigidly mounted upon the left end of the shaft 56 of the feed-chute 55 is a worm-wheel 64 located in a plane parallel with and just outwardly of the outer face of the left track-ring 15 and meshed into by a worm 65 as is especially well shown in Figs. 2 and 5.

The worm 65 above referred to is rigidly mounted upon the inner end of a control-shaft 66 extending in parallelism with the left side of the structure and having a hand-wheel 67 rigidly mounted upon its outer end and preferably located in a plane slightly beyond the outer surface of the peripheral wall 11. The said control-

shaft 66 is mounted for rotary movement adjacent its inner end in a bracket 68 extending outwardly from the left side-plate 43, and adjacent its outer end the said control-shaft is mounted for rotation in a bracket 69 upstanding from the left frame-member 19 as is especially well shown in Fig. 2.

Intermediate the outer face of the bracket 69 and the inner face of the hand-wheel 67, the control-shaft 66 has rigidly mounted thereon a toothed locking-wheel 70 which is adapted to be releasably-engaged by a pawl 71 mounted at the upper end of the bracket 69 as is shown in Figs. 1 and 2. The engagement of the pawl 71 with the locking-wheel 70 serves to positively hold the control-shaft 66 against unintentional rotation due to vibration or the like.

To the rear of the center-roll shaft 26 the stationary left side-plate 43 is formed with an opening 72 for the reception of a pivotal discharge-chute 73. As is especially well shown in Fig. 5, the discharge-chute 73 is provided adjacent its inner end with a transverse trunnion-shaft 74 which projects at its respective opposite ends beyond the respective opposite sides of the discharge-chute 73, and is supported for turning movement in lugs 75—75 projecting outwardly from the outer face of the left side-plate 43, as is shown in Fig. 2.

Normally the discharge-chute 73 is tilted inwardly-and-downwardly as is shown by full lines in Figs. 2, 5 and 6 in which position the inner end of the said chute extends but slightly inwardly through the left side-plate 43, as will appear from an inspection of Fig. 6.

When the discharge-chute 73 is turned into its outwardly-and-downwardly-inclined position as indicated by the broken lines in Figs. 5 and 6, the inner end of the said discharge-chute projects well into the interior of the housing 10 and in position to receive material dropping from the lifting-plates 54 either directly into the open inner end of the said discharge-chute or onto a deflecting-plate 76 which is secured to the right side-plate 44 as is indicated in Fig. 6, and is so inclined as to feed material directly into the open inner end of the discharge-chute 73.

The pivots (the opposite ends of the trunnion-shaft 74) of the discharge-chute 73 are so positioned that the outer portion of the said discharge-chute is the heaviest and tends to descend by gravity to thus coincidentally elevate its inner end. For the purpose of controlling the movement of the discharge-chute 73 into and out of the position in which it is shown by full lines or the position in which it is shown by broken lines in Figs. 5 and 6, the said discharge-chute has attached to its outer portion a cable 77 or other suitable flexible member which has its opposite end secured to and wound upon a wind-up reel 78 mounted upon the control-shaft 66 before referred to.

From the foregoing it will be seen that by turning the hand-wheel 67 in a counterclockwise direction as viewed in Fig. 5, the discharge-chute 73 may be swung from the position in which it is shown by full lines in Fig. 5 into its discharge position in which it is shown by broken lines in the same figure. Simultaneously with the described movement of the discharge-chute 73, the feed-chute 55 will be swung from its active position in which it is shown by full lines in Fig. 5 into its retired position in which it is shown by broken lines in the same figure. The retirement of the feed-chute 55 as just above described will

permit the material being lifted and dropped by the lifting-plates 54 to fall unhindered by the feed-chute 55 onto the deflecting-plate 76 and into the open inner end of the discharge-chute 73 for passage outwardly into any suitable receptacle.

On the other hand, should the hand-wheel 67 be turned in a clockwise direction as viewed in Fig. 5, the discharge-chute 73 will be shifted by means of the cable 77 from the position in which it is shown by broken lines in Fig. 5 into the position in which it is shown by full lines in the same figure. At the same time that the discharge-chute 73 is being shifted as described the feed-chute 55 will be shifted from the position in which it is shown by broken lines in Fig. 5 back into the position in which it is shown by full lines in the same figure to thereby feed the material elevated by the lifting-plates 54 directly between the grinding-rolls 42 and 46.

Located between and extending in parallelism with the frame-members 19 and 25 is a trough or tank 79 in which the lower portion of the housing 10 revolves.

Operation

Friable material to be ground or crushed may be introduced into the interior of the housing 10 in any suitable manner such for instance as by charging the said material through the discharge-chute 73 while the latter is in its upwardly-and-outwardly-inclined position as shown by full lines in Figs. 5 and 6. The said friable material will be lifted by the lifting-plates 54 and continuously dropped upon the upper surface of the feed-chute 55 to slide onto the periphery of the center grinding roll 42.

As the material is fed onto the center grinding-roll as above described, it will pass beneath the eccentric grinding-roll 46 and will be crushed. During the grinding operation large pieces of rock, cinders, clinkers or other friable material passing between the grinding-rolls 42 and 46 will cause the latter grinding-roll to rise and fall similarly moving its shaft 45. The respective opposite ends of the shaft 45 will be held to substantially correspondingly up-and-down movement by the guide-arms 49 and 53 in conjunction with the coupling-shaft 50.

During the vertical movement of the eccentric grinding-roll 46 and its shaft 45 the respective opposite ends of the said shaft will play up and down in the arcuate clearance-slots 47 and 48 respectively formed in the side-plates 43 and 44.

The friable material will of course ultimately pass from between the grinding-rolls 42 and 46 and will drop into the bottom of the housing 10 to be again lifted by the lifting-plates 54 and reground as much as desired.

During the grinding operation water may be circulated through the lower portion of the housing 10 from the trough or tank 79 so that friable materials may be washed out as rapidly as they are ground and only the coarser particles again elevated for regrinding in the manner above described.

When it is desired to discharge the contents of the housing 10 the control-shaft 66 will be turned by means of its hand-wheel 67 to swing the feed-chute 55 into the position in which it is shown by broken lines in Fig. 5 and to simultaneously swing the discharge-chute 73 into the position in which it is shown by broken lines in Fig. 5. Thereafter solid material contained within the housing 10 will fall off from the lifting

plates 54 and instead of being guided between the two grinding-rolls 42 and 46 the said material will pass outwardly through the discharge-chute 73.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A grinding-mill, including in combination: a rotary housing having a peripheral wall and an opening at each side; two opposite stationary side-plates respectively forming closures for the sides of the said housing, one of the said side-plates being provided with a chute-receiving opening; lifting-ledges within the said rotary housing and movable therewith; means for turning the said rotary housing; a center crushing-roll located between the said stationary side-plates and encircled by the said housing; means for turning the said center crushing-roll; an eccentric crushing-roll also located between the said side-plates and positioned to coact with the surface of the said center crushing-roll; guide-means for the said eccentric crushing-roll; a movable feed-chute located within the said housing and movable into and out of position to convey material from the said lifting-ledges to a point between the two said crushing-rolls; a discharge-chute extending through the chute-receiving opening in the aforesaid side-plate of the housing and movable into an outwardly-tilting and an inwardly-tilting position, with its inner portion extending in position to receive material from the said lifting-ledges when the said feed-chute is retired; and control-means positively connected to both the said feed-chute and the said discharge-chute to positively move both thereof and constructed and arranged to coincidentally positively move the said feed-chute into its operative position and to tilt the said discharge-chute into its inwardly-tilted position.

2. A grinding-mill, including in combination: a rotary housing having a peripheral wall and an opening at each side; two opposite stationary side-plates respectively forming closures for the sides of the said housing, one of the said side-plates being provided with a chute-receiving opening; lifting-ledges within the said rotary housing and movable therewith; means for turning the said rotary housing; a center crushing-roll located between the said stationary side-plates and encircled by the said housing; means for turning the said center crushing-roll; an eccentric crushing-roll also located between the said side-plates and positioned to coact with the surface of the said center crushing-roll; guide-means for the said eccentric crushing-roll; a pivotal feed-chute located within the said housing and pivoted at a point closely adjacent the said crushing-rolls and having a swinging end movable into and out of position closely adjacent the said lifting-ledges; a discharge-chute extending through the chute-receiving opening in the aforesaid side-plate of the housing and pivoted intermediate its respective opposite ends for being tilted into and out of an outwardly-tilted position, the said discharge-chute being constructed and arranged to have its inner end positioned to receive material from the said lifting-

ledges when the discharge-chute is tilted into its outwardly-tilted position; and control-means positively connected to both the said feed-chute and the said discharge-chute to positively move both thereof and constructed and arranged to positively coincidentally move the said feed-chute into its operative position and to tilt the said discharge-chute into its inwardly-tilted position

3. A grinding-mill, including in combination: a rotary housing having a peripheral wall and an opening at each side; two opposite stationary side-plates respectively forming closures for the sides of the said housing, one of the said side-plates being provided with a chute-receiving opening; lifting-ledges within the said rotary housing and movable therewith; means for turning the said rotary housing; a center crushing-roll located between the said stationary side-plates and encircled by the said housing; means for turning the said center crushing-roll; an eccentric crushing-roll also located between the said side-plates and positioned to coact with the surface of the said center crushing-roll; guide-means for the said eccentric crushing-roll; a pivotal feed-chute located within the said housing and pivoted at a point closely adjacent the said crushing-rolls and having a swinging end movable into and out of position closely adjacent the said lifting-ledges; a discharge-chute extending through the chute-receiving opening in the aforesaid side-plate of the housing and pivoted intermediate its respective opposite ends for being tilted into and out of an outwardly-tilted position, the said discharge-chute being constructed and arranged to have its inner end positioned to receive material from the said lifting ledges when the discharge-chute is tilted into its outwardly-tilted position; and control-means including a rotary control-shaft, a wind-up member driven by the said control-shaft, a flexible member connected at one end to the outer portion of the said discharge-chute for tilting the same and connected at its opposite end to the said wind-up member, a first gear also operatively connected to the said rotary control-shaft for being turned thereby, and a second gear-member coacting with the said first gear-member and connected to the said feed-chute for tilting the same coincidentally with the tilting of the said discharge-chute by the said flexible member.

4. A grinding-mill, including in combination: a rotary housing having a peripheral wall and an opening at each side, two opposite stationary side-plates respectively forming closures for the sides of the said housing, one of the said side-plates being provided with a chute-receiving opening; lifting-ledges within the said rotary housing and movable therewith; means for turning the said rotary housing; a center crushing roll located between the said stationary side-plates and encircled by the said housing; means for turning the said center crushing-roll; an eccentric crushing-roll also located between the said side-plates and positioned to coact with the surface of the said center crushing-roll; guide-means for the said eccentric crushing-roll; a pivotal feed-chute located within the said housing and pivoted at a point closely adjacent the said crushing-rolls and having a swinging end movable into and out of position closely adjacent the said lifting-ledges; a discharge-chute extending through the chute-receiving opening in the aforesaid side-plate of the housing and pivoted intermediate its respective opposite ends for being tilted into and out of an outwardly-tilted position, the said discharge-chute being constructed and arranged to have its inner end positioned to receive material from the said lifting-

mediate its respective opposite ends for being tilted into and out of an outwardly-inclined position, the said discharge-chute being constructed and arranged to have its inner end positioned to receive material from the said lifting-ledges when the discharge-chute is tilted into its outwardly-inclined position; a rotary control-shaft; a reel mounted on the said control-shaft; a flexible cord-like member connected at one end to the outer portion of the said discharge-chute for tilting the same and connected at its opposite end to the said reel for being wound thereon; a worm also carried by the said control-shaft; and a worm-wheel connected to the said feed-chute and meshing into the said worm for being turned thereby to tilt the said feed-chute coincidentally

with the tilting of the said discharge-chute by the said flexible member.

CHAS A. DREISBACH.
